UNITED STATES PATENT OFFICE

LAWRENCE G. SHOOK, OF LOS ANGELES, CALIFORNIA

ELECTRIC HAMMER

Application filed October 20, 1926. Serial No. 142,863.

This invention relates to improvements in electric hammers.

An object of the invention is to provide an improved electric hammer of simple and durable construction in which precautionary measures have been taken against wear of the various parts and wherein means is provided for taking up the wear which must necessarily occur upon worn parts.

Another object of the invention is to provide an improved electric hammer wherein there is a shaft driven by the rotor of an electric motor and to provide a yieldable connection between the shaft and the rotor so that shocks imparted to the shaft will not be transmitted to the rotor because of the yieldable connection.

Another object of the invention is to provide an electric hammer wherein there is a housing in which is disposed an electric motor, a shaft carrying a cam driven by the motor, a tool holder slidably mounted upon the housing and having a cam adapted to be engaged by the mentioned cam and to provide a spring construction which is adjustable and which serves to urge the tool holder into such position that its cam will normally be held disengaged from the cam on the shaft so that in order to cause the tool to be hammered it is necessary to force the housing toward the tool holder overcoming the action of the spring construction.

With the foregoing and other objects in view which will be made manifest in the following detailed description, and specifically pointed out in the appended claims, reference is had to the accompanying drawing for an illustrated embodiment of the invention, wherein:

Figure 1 is a vertical, longitudinal section through the improved electric hammer.

Fig. 2 is a transverse section taken substantially upon the line 2—2 on Figure 1.

Fig. 3 is a transverse section taken upon the line 3—3, upon Figure 1.

Referring to the accompanying drawings wherein similar reference characters designate similar parts throughout, the improved electric hammer consists of a housing shown as built up of three parts. The central part,

which is cylindrical in form, is indicated at 10, and has a cap 11 and a third part 12 secured thereto as by screws 13.

The third part 12 is provided with a tubular extension 14. Within the housing there is disposed an electric motor, the field or stator of which indicated at 15 is rigidly mounted upon the interior of the center section 10 of the housing. The rotor of the motor is indicated at 16. The drawing illustrates the motor as being a direct current motor having brushes 17. It will of course be understood that any other suitable type of motor may be employed, either direct current or alternating current. Current is supplied to the motor through a cable 18, controlled by a switch 19 operable by a finger 20 pivotally mounted upon the handle 21 which is integral with or secured to the cap 11.

Within the housing there is disposed a shaft divided into two sections 22 and 23. These sections are connected to each other by a tongue and groove connection 24 located within the rotor 16. The rotor 16 is loosely mounted upon the shaft but is capable of rotating the shaft because of the tongue and groove connection between one of its hubs and a collar 25 which is keyed and pinned to the shaft section 22. The shaft section 22 is disposed within the tubular extension 14 and two bushings 26 and 27 are mounted in the tubular extension, forming bearings for the shaft section. The bushing 27 may be pressed into or otherwise secured to the tubular extension whereas the bushing 26 is preferably threaded into the tubular extension. The collar 25 bears against the bushing 26, and on the other end of the shaft section 22 there is keyed and pinned a collar 28 bearing against the bushing 27. The collars 25 and 28 bearing against the bushings 26 and 27 respectively resist axial movement of the shaft section 22 and wear on these bushings can be taken up by screwing out the bushing 26.

This can be accomplished by inserting a pin 30 into the recess 29 through the aperture 30 formed in the housing section 12 and which is normally closed by a door 31.

On the lower end of the shaft section 22 there is rigidly secured a cam 32 adapted to

engage a cam 33 mounted upon the tool holder 34. The tool holder 34 consists of a tubular body into which the stem 35 formed integral with the cam 33 extends. Within the body forming the tool holder there is formed a shoulder on which seats a hard metal cap 36, having its face concaved complementary to the convexed end of the tool 37 fitting in the body. A diametrical aperture is formed through the tool holder 34 to receive a wedge 38 and this aperture is so constructed that when the wedge is driven into it that the wedge will be frictionally held in position therein. An aperture 39 is formed in the body of the tool 37 and is of such size that the wedge 38 loosely extends through it. From this construction it will be understood that the tool 37 is loosely held in the tool holder 34, the wedge 38 serving to merely hold the tool from dropping out of the tool holder. The particular tool employed may be different under various circumstances; for example, it may be a chisel, a punch, a rivet hammer, or any other desirable tool. One tool 40 can be substituted for another by indicating at the wedge 38 and replacing it after the new tool has been placed in the tool holder. The wedge is preferably fastened to the tool holder by a chain 40 to prevent its becoming lost.

An inside sleeve 41 is fastened to the tool holder 34 by a nut or union joint 42 which is held on the tool holder by the shoulder 43. This inside sleeve extends from the tubular extension 14 and has longitudinal grooves 44 formed upon its interior surface which receive splines 45 formed on the tubular member 14. In this manner the tool holder 34 and the sleeve 41 are held against rotation relatively to the housing, but they are capable of sliding longitudinally relatively to the housing. On the exterior surface of the cam 33 there are also formed splines as shown upon Figure 3 which fit within the groove 44 so that this cam will also be held against rotation relatively to the housing. An outside sleeve 46 is threaded on to the tubular extension against shims 47 positioned against a shoulder thereon. This outside sleeve has such an internal diameter as to slidably receive an annular flange 48 formed on the exterior surface of the sleeve 41. It is locked against unscrewing by a split ring 49, fitting in a groove on its exterior surface, one end of the split ring being bent radially inward through the sleeve and through an aperture formed in the tubular extension. A similar lock indicated at 50 locks the nut 42 from unscrewing from the inside sleeve 41. Within the outer sleeve 46 there are arranged two spiral springs 51 and 52, the spring 51 being compressed between the flange 48 and a shoulder on the tubular extension, and the spring 52 being compressed between the flange 48 and a gland 53 threaded into the

open end of the outer sleeve 46. The gland 53 has notches upon its periphery in which a leaf spring 54 which is fastened to the outside sleeve is adapted to seat. The spring 54 locks the gland 53 from unscrewing but permits it to be tightened or loosened to adjust the compression of the springs 51 and 52.

The sleeve 46 contains a lubricant and to prevent this lubricant from leaking out of the sleeve, the gland 53 provides a stuffing box 55 which is closed by a packing gland 56 threaded on to the gland 53. The two springs 51 and 52 work in opposition to each other and they normally hold the inside sleeve 41 in such position that the tool holder 34 will have its cam 33 disengaged from the cam 32. By forcing the housing toward the tool holder, the spring 51 will be further compressed and the two cams 32 and 33 can be caused to engage. Normally it is desired that when no pressure is applied to the housing that the two cams 32 and 33 just clear each other. In order to provide for adjustment and to take up wear on the engaging surface of the cams the gland 53 can be tightened or loosened; this provides a very fine adjustment. Further adjustment can be provided by removing the outside sleeve 46 and taking out or inserting one or more shims 47.

The opposed faces of the collar 25 and the most adjacent hub of the rotor 16 are hollowed out and a spiral spring 57 is disposed about the shaft section 22 and compressed between them. On the opposite side of the rotor 16 a collar 58 is secured to the shaft section 23 and the opposed faces of this collar and the most adjacent hub of the rotor are also hollowed out to accommodate a spiral spring 59. The two springs 57 and 59 work in opposition to each other upon the rotor 16 and as the rotor is loosely mounted upon the shaft it may be considered as floating thereon between the springs. In this way any shock which is imparted to the shaft section 22 will not be transmitted to the rotor 16 because of the springs, thus preventing damage to the rotor.

On the end of the shaft section 23 there is formed a shoulder against which is disposed the inner race of a ball bearing 60. This inner race is held against the shoulder by a nut 61. The outer race fits upon the interior of the cap 11. The tongue and groove connection 24 is a relatively loose one, permitting a small degree of longitudinal movement of the shaft section 23 relatively to the shaft section 22. This brake in the shaft is for the purpose of preventing the shaft from pounding out the bearing 60. If there should be a small amount of play between the collar 25 and the bushing 26, shocks imparted to the shaft 22 will not be transmitted to the shaft section 23 so as to pound out the bearing 60 because of this brake 24. The ends of the shaft sections 22 and 23, near the brake 24,

fit snugly within the rotor 16 and are held thereby in alignment so that, although the rotor is loose upon the shaft, it will be held thereby centrally of the stator 15.

The operation of the improved hammer is as follows: The tool 37 is placed against the article to be hammered and by operating the lever 20 the rotor 16 will be caused to revolve, revolving the shaft 22 and the cam 32. The handle 21 is not pressed with sufficient pressure to cause the cams 32 and 33 to engage until the rotor is rotating at a maximum speed, then by forcing the housing toward the tool holder the cams can be caused to engage so that the tool 37 will be vibrated and hammered. The magnitude of each blow imparted to the tool 37 varies with the pressure applied to the handle 21. The second handle 62 is preferably secured to the housing, assisting in moving the housing about and in holding it in the desired position.

From the above described construction it will be appreciated that a novel electric hammer is provided which cannot easily get out of order for the reason that the wearing parts are adequately protected. Furthermore, the improved hammer may easily and quickly be constructed and in the event that certain parts should require repair or replacement it may be easily and quickly assembled to accomplish this purpose.

It will be understood that various changes may be made in the details of the construction without departing from the spirit and scope of the invention as defined by the appended claims.

I claim:

1. An electric hammer comprising a housing, an electric motor in the housing, a shaft driven by the motor, a cam carried by the shaft, a tool holder slidably upon the housing, a cam on the tool holder adapted to be engaged by the first cam, said tool holder carrying a sleeve disposed around the housing and on which is formed a flange, springs bearing on opposite sides of the flange and yieldably holding the tool holder in the predetermined position wherein the cams are disengaged, whereby, upon forcing the housing toward the tool holder, the cams will engage, causing the tool holder to be vibrated by the motor.

2. An electric hammer comprising a housing, an electric motor in the housing, a shaft driven by the motor, a cam carried by the shaft, a tool holder carrying a sleeve slidably keyed upon the housing, said sleeve having a flange thereon, an outer sleeve secured to the housing and disposed about the first sleeve, a gland threaded into the open end of the outer sleeve, a spring compressed within the outer sleeve between the flange and the housing, a second spring compressed within the outer sleeve between the flange and the gland, and a cam carried by the tool holder engageable by the mentioned cam.

3. An electric hammer comprising a housing having a tubular extension, an electric motor in the housing, a shaft rotatably mounted in the tubular extension and extending through the rotor of the motor, a cam carried by the shaft, a tool holder having a sleeve disposed about the tubular extension, the said sleeve having a splined connection with the extension, a cam carried by the tool holder engageable by the first cam, there being a flange on the exterior of said sleeve, an outer sleeve secured to the housing and disposed about said sleeve, a spring compressed between the flange and the housing, a gland threaded into the outer sleeve, and a spring compressed between said flange and said gland, said springs serving to normally hold the tool holder in that position wherein the cams are disengaged.

4. An electric hammer comprising a housing having a tubular extension, an electric motor in the housing, a shaft rotatably mounted in the tubular extension and extending through the rotor of the motor, a cam carried by the shaft, a tool holder having a sleeve disposed about the tubular extension, the said sleeve having a splined connection with the extension, a cam carried by the tool holder engageable by the first cam, there being a flange on the exterior of said sleeve, an outer sleeve secured to the housing and disposed about said sleeve, a spring compressed between the flange and the housing, a gland threaded into the outer sleeve, and a spring compressed between said flange and said gland, said springs serving to normally hold the tool holder in that position wherein the cams are disengaged, there being bushings mounted in the ends of the tubular extension through which the shaft extends, and collars on the shaft bearing against said bushings so as to prevent axial movements of the shaft.

5. An electric hammer comprising a housing having a tubular extension, an electric motor in the housing, a shaft rotatably mounted in the tubular extension and extending through the rotor of the motor, a cam carried by the shaft, a tool holder having a sleeve disposed about the tubular extension, the said sleeve having a splined connection with the extension, a cam carried by the tool holder engageable by the first cam, there being a flange on the exterior of said sleeve, an outer sleeve secured to the housing and disposed about said sleeve, a spring compressed between the flange and the housing, a gland threaded into the outer sleeve, and a spring compressed between said flange and said gland, said springs serving to normally hold the tool holder in that position wherein the cams are disengaged, there being bushings mounted in the ends of the tubular extension through which the shaft extends, and collars on the shaft bearing against said bushings so

as to prevent axial movements of the shaft, the rotor of the motor being loose upon the shaft and having a tongue and groove connection with one of said collars, and spring means urging the rotor into a predetermined position upon the shaft.

In testimony whereof I have signed my name to this specification.
